DESIGN FOR A COMBINED LAMP AND MIRROR

Phillip E. Merrill and Oliver R. Titchenal,
Santa Monica, Calif.

Application August 26, 1947, Serial No. 141,076

Term of patent 14 years

(Cl. D86—10)

To all whom it may concern:

Be it known that we, Phillip E. Merrill and Oliver R. Titchenal, citizens of the United States and residents of Santa Monica, in the county of Los Angeles and State of California, have invented a new, original, and ornamental Design for a Combined Lamp and Mirror, of which the following is a specification, reference being had to the accompanying drawing, forming a part thereof.

Figure 1 is a front view of a combined lamp and mirror, showing our new design;

Figure 2 is a side view of the combined lamp and mirror;

Figure 3 is a back view;

Figure 4 is a top view of the same;

Figure 5 is a perspective view, on a slightly larger scale, taken from the front of the combined lamp and mirror, showing our new de-

sign; and Figure 6 is a perspective view, on the same scale as Figure 5, taken from the rear of the same.

We claim:

The ornamental design for a combined lamp and mirror, substantially as shown.

PHILLIP E. MERRILL,
OLIVER R. TITCHENAL.
